US00D515278S

(12) **United States Design Patent** (10) Patent No.: **US D515,278 S**
Jendrucko et al. (45) Date of Patent: **** Feb. 21, 2006**

(54) **THREE DIMENSIONAL BANDANA**

(76) Inventors: **Mary L. Jendrucko**, 2704 W. 176th St.,
 Torrance, CA (US) 90504; **Paul J. Jendrucko**, 2704 W. 176th St.,
 Torrance, CA (US) 90504

(**) Term: **14 Years**

(21) Appl. No.: **29/197,661**

(22) Filed: **Jan. 16, 2004**

(51) LOC (8) Cl. **02-05**

(52) U.S. Cl. **D2/500; D30/145**

(58) Field of Classification Search **D2/500, D2/501, 600, 602, 605, 609, 865; 2/144-146, 2/155-157, 46, 102, 207, 410, 98; D30/144, D30/145, 152; 119/714, 715, 792, 856, 857**

(57) **CLAIM**

The ornamental design for a three dimensional bandana, substantially as shown and described.

DESCRIPTION

FIG. 1 is a front elevational view of a three dimensional bandanna showing our new design;

FIG. 2 is a rear elevational view thereof;

FIG. 3 is a side elevational view thereof, the opposite side is a mirror image thereof;

FIG. 4 is a top plan view thereof;

FIG. 5 is a bottom plan view thereof;

FIG. 6 is a front isometric view thereof; and,

FIG. 7 is a rear isometric view thereof.
